(57) **CLAIM**

The ornamental design for a storage box for calibration weights, as shown and described.

DESCRIPTION

FIG. 1 is a top-right perspective view of an embodiment of the storage box for calibration weights;

FIG. 2 is a right side elevation view, the left side view being a mirror image thereof;

FIG. 3 is a front elevation view;

FIG. 4 is a rear elevation view; and,

FIG. 5 is a top plan view, the bottom view being a mirror image thereof.
